The ornamental design for a burner as shown and described.

DESCRIPTION

FIG. 1 is a first perspective view of a burner showing our new design disposed in a griddle.

FIG. 2 is a second perspective view of the burner showing our new design disposed in the griddle.

FIG. 3 is a third perspective view of the burner, shown independent of the griddle, to show aspects of the design not visible when combined.

FIG. 4 is a fourth perspective view of the burner.

FIG. 5 is a front view thereof.

FIG. 6 is a back view thereof.

FIG. 7 is a first side view thereof.

FIG. 8 is a second side view thereof.

FIG. 9 is a top view thereof; and,

FIG. 10 is a bottom view thereof.

The broken lines shown in the Figures show environment and portions of the burner that form no part of the claimed design.

The shade lines in the Figures show contour and do not claim surface ornamentation or treatment.
